UNITED STATES PATENT OFFICE.

HAROLD L. HOLLOWAY, OF COLUMBUS, OHIO.

TOY.

Application filed July 14, 1926. Serial No. 122,408.

My invention relates to a wheeled toy and particularly to a toy embodying elements that will require the child to take exercise in operating the toy.

5 The general object of my invention is to provide a wheeled exercising toy that may be easily operated and which will be effective with respect to its exercising features.

10 The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a perspective view of a toy embodying my invention;

Figure 2 is a transverse vertical section 20 on the line 2—2, Figure 4;

Figure 3 is a transverse vertical section on the line 3—3, Figure 4;

Figure 4 is a longitudinal vertical section on the line 4—4, Figure 2.

25 In carrying out my invention in accordance with the illustrated example, a body is provided consisting of side boards 10 united at the front by an oblique transverse piece 11. At the top of the body is a longitudinal board or flat member 12 hinged at its front end as 13 to the body and extending to the rear end, there being a vertical slot 14 in said top element 12 for a purpose that will appear. The element 12 constitutes a

30 seat for the operator of the vehicle and for the purpose has a seat back 15 rising from the rear end. Also, a raised block 16 is provided, forward of the seat back 15. The numeral 17 indicates the front wheel; 18 the

40 front axle which passes transversely through broad standards 19 integral with a head 20 at the upper ends of said standards through which head a king pin 21 passes. For strength the pin 21 passes also through an integral cross piece 22 on head 20 and through a wear plate 23 to which said pin 21 is riveted. The lower end of the pin receives a transverse pin or cotter 24 below the head 20. Reverting to the axle 18 the same

45 projects beyond the outer sides of the standards 19 (see Figure 3) and it receives foot rests 118, the inner ends of which are formed with axial sockets to receive the axle ends.

50 In order to provide for exercising movement in my improved toy, a lever 25 is disposed lengthwise of the vehicle between the

sides 10 and in practice said lever is advantageously provided with a head 125 extending upwardly through the slot 14 in seat 12 and made to simulate an animal, fowl, or the like, to make the toy attractive to a child. 60

The lever 25 is fulcrumed on the transverse pin 26 supported on the sides 10 and it is formed with an extension 27 in the rear of the fulcrum 26 at the lower edge of the 65 lever 25 and the extension 27 metallic bars 28 are fixed as by screws 29. Said bars 28 project rearwardly beyond the lever extension 27 and their rear ends are pivotally connected as at 30 to one end of a link 31, 70 the opposite end of which link 31 is pivotally connected with a crank 32 on a transverse axle 33 of the rear wheel 34, said wheels having the hubs secured to the axle 33 to turn therewith as, for example, by 75 transverse pins 35 passing through said slots and axle and by a cotter pin 36. The axle 33 is formed also with auxiliary cranks 37 at the sides of the central crank 32 and said auxiliary cranks 37 have pivotally secured 80 thereto the lower ends of lift bars 38, the upper ends of which are formed with trunnions 39 supported in hanger bearings 40 in the form of U-shaped brackets secured rigidly to the under side of said seat 12. The 85 described arrangement constitutes, it will be observed, a drive for the rear axle 33 as well as an operating means for vertically vibrating the seat 12. This is so because the rocking of the lever 25 through link 31 90 will turn the crank 32 and axle 33 as well as the auxiliary cranks 37, which serve to give up and down movement to the lift bars 38 of seat 12. Hence, a child seated on the seat 12 adjacent to seat back 15 and with the 95 child's feet on the foot rests 18, the vibrating movement may be imparted to the lever 25 for actuating the drive axle 36 and described parts appurtenant thereto. The block 16 prevents forward sliding of the 100 child on the seat 12. The operation of the lever 25 may be effected by the child grasping handles 41 at the sides of the head 125. The axle 33 in the illustrated example turns in hanger bearings 42 suitably secured by 105 bolts or the like to a rectangular frame 43, the front and rear cross bars of which are held rigid with the sides 10.

I would state in conclusion that while the illustrated example constitutes a practical embodiment of my invention, I do not limit myself strictly to the exact details herein 110

illustrated, since, manifestly, the same can be considerably varied without departure from the spirit of the invention as defined in the appended claim.

5 Having thus described my invention, I claim:

In a child's vehicle, a frame, a drive axle having wheels mounted to turn therewith, a vertically rocking lever, a seat element

hinged at its front end, said lever having a head extending upwardly through said seat element, said axle having a crank connected with one end of said lever to turn the axle with the vibration of the lever, auxiliary cranks on said axle and lift bars connected with said auxiliary cranks and with said seat elements.

HAROLD L. HOLLOWAY.
